(57) **CLAIM**

The ornamental design for a decoration base for toy beads, as shown and described.

DESCRIPTION

FIG. 1 is a perspective view of portions of the top and left sides of a decoration base for toy beads showing my new design;

FIG. 2 is a perspective view of portions of the bottom and left sides thereof;

FIG. 3 is a front view thereof;

FIG. 4 is a rear view thereof;

FIG. 5 is a top view thereof;

FIG. 6 is a right side view thereof; and,

FIG. 7 is a left side view thereof.

The broken lines shown are included for the purpose of illustrating portions of the article which form no part of the claimed design.

1 Claim, 7 Drawing Sheets
